R. S. WATT

ALARM CLOCK

Filed Dec. 1, 1922

Robert S. Watt,
By his Attorney, Geo. W. Heath

UNITED STATES PATENT OFFICE.

ROBERT S. WATT, OF BROOKLYN, NEW YORK.

ALARM CLOCK.

Application filed December 1, 1922. Serial No. 604,299.

To all whom it may concern:

Be it known that I, ROBERT S. WATT, a citizen of the United States, and a resident of the borough of Brooklyn, county of Kings, city and State of New York, have invented certain new and useful Improvements in Alarm Clocks, of which the following is a specification sufficient to enable those skilled in the art to which the invention appertains to utilize the same.

My improvements relate to alarm clocks generally, and particularly to the class thereof in which provision is made for a primary and secondary alarm as heretofore known in the state of the art. My object is to provide means, to be incorporated in the clock-work as manufactured, or capable of application thereto thereafter as an attachment, whereby an incipient warning may be effected automatically by the resonator a prescribed time before that set for the release of the main or prolonged alarm, so that the latter may be shut off manually and entirely, for the time being, if so desired, as when unnecessary or undesirable under the circumstances; or may otherwise in due course be allowed to ring continuously for a definite period, as heretofore. To this end, my invention consists in the specific construction, combination and arrangement of parts and appurtenances herein described and claimed, whereby the alarm mechanism is actuated and controlled, all as hereinafter fully set forth.

In the accompanying drawings I exemplify a practical embodiment of the essential features of my invention in conjunction with a clock movement of well known type, although I do not limit myself to the identical form and construction of parts shown, since changes and modifications may be resorted to in minor details in adapting my improvement to various combinations of arrangements of clock work without departing from the spirit and intent of my invention in this respect.

With this understanding,

Fig. 1, represents an elevation of one side of a clock work frame, and portions of a clock work of well known type;

Fig. 2, is a lower end view of the frame showing the essential parts of my alarm control device in locking position;

Fig. 3, is a like view showing the position of the parts when the incipient alarm is actuated;

Fig. 4, is a top view of the alarm setting spindle, and the cam wheel mounted thereon, on an enlarged scale;

Fig. 5, is a side view of the parts shown in Fig. 4;

Fig. 6, is a sectional elevation taken upon plane of line 6—6, Fig. 4;

Fig. 7, is a detail view of the alarm escapement spring pawl;

Figs. 8 to 10 inclusive, are end views of said alarm escapement spring pawl, illustrating its function as related to the alarm escapement wheel;

Fig. 11, is a diagrammatic representation of a portion of the alarm escapement wheel and the escapement pawl teeth as related thereto.

F, represents the supporting frame of a clock movement of any ordinary type, parts only of the works being shown in Fig. 1, sufficient to indicate the co-relation of my alarm control device therewith. Thus a, represents the alarm escapement wheel which, when released, actuates the resonator hammer h, through the medium of the rock lever r, and its connection rod r', in a manner well known in the art, said rock lever r, being held normally by the dog d, controlled by the time mechanism of the clock in the usual way.

S, is my spring pawl for the control of the aforesaid alarm escapement a, when the rock lever r, is released by the dog d. The rear portion of said spring pawl S, is rigidly attached to the frame F, as indicated in Fig. 1, and its forward or operative extremity is bent over substantially at right angles to the shank to constitute the detent member s, formed with a shoulder s', and tooth s², the latter being longer, or of greater projection, than the aforesaid shoulder s', as will be seen by reference more particularly to Figs. 8, 9 and 10, of the drawings. The elastic resilience of the spring S, tends constantly to hold the shoulder s', and the tooth s², out of engagement with the teeth of the alarm escapement wheel, as in Fig. 10.

E, is the alarm setting spindle mounted upon and between the front and rear side plates of the frame F, as shown more particularly in Fig. 2, of the drawings, and provided with the usual knurled setting handle e, (Fig. 2) at one extremity. At or near its other extremity it has rigidly attached to it a finger e', for contact with the edge of an

annular cam h , integral with the gear wheel K , which is slidably and rotatably mounted on said alarm setting spindle E , but otherwise independent thereof. This gear wheel K , meshes with a pinion p , driven by the main train of clock gearing.

The spring pawl S , bears against the hub h^x , of the gear wheel K , as shown more particularly in Figs. 2, 3 and 6, of the drawings, and thereby tends constantly to hold the edge of the annular cam h , against the finger e' , of the alarm setting spindle E . Said annular cam h , is formed with a concentric portion h' , of uniform height as related to its gear wheel K , and with a minor depression or shoulder h^2 , and a major depression h^3 , the latter connected with the concentric level portion h' of the cam h , by the incline h^4 , as shown more particularly in Figs. 4 and 5, of the drawings.

As a consequence of this construction and arrangement of parts, when the rotation of the gear wheel K , brings the minor depression h^2 , into coincidence with the finger e' , of the alarm setting spindle E , the spring S , forces the said wheel K , outward until said finger contacts with the shoulder forming the bottom of said minor depression h^2 as shown in Fig. 3, of the drawings,—thereby allowing the said spring pawl S , to withdraw its shoulder s' , from in front of the tooth (1) of the alarm escapement wheel a , with which it has been in contact, and permitting the alarm escapement wheel a , to advance until the next succeeding tooth (2) thereof contacts with the tooth s^2 , of the spring pawl S , as indicated in Fig. 9, of the drawings. This preliminary or initiative movement of the alarm escapement wheel a , is sufficient to effect a single stroke of the hammer h , causing the resonator to sound the incipient alarm. When the continued rotation of the gear wheel K , brings the major depression h^3 , into coincidence with the finger e' , of the alarm setting spindle E , the spring pawl again raises the wheel K , and cam h , until the finger e' , contacts with the bottom of the major depression h^3 , of said cam h ,—thereby effecting the clearance of the pawl tooth s^2 , from engagement with the alarm escapement wheel a , as indicated in Fig. 10, of the drawings, so that said alarm escapement wheel is free to rotate and sound the major

alarm. The continued rotation of the wheel K , with the finger e' , in contact with the cam incline h^4 , causes the depression of the cam and wheel K , and the re-engagement of the spring pawl shoulder s' , and tooth s^2 , with the teeth of the alarm escapement wheel a , as shown in Fig. 8.

In Fig. 11, I have illustrated diagrammatically this engagement of the pawl shoulder s' , and pawl tooth s^2 , with the teeth of the alarm escapement wheel a , in solid lines, and in dotted lines, the incipient movement of said wheel when the pawl shoulder s' , is withdrawn from contact with said alarm escapement wheel.

The time between the sounding of the incipient or minor alarm and that of the major alarm will obviously be governed by the distance between the minor depression h^2 , and the major depression h^3 , and this will be prescribed in the formation of the cam, as for five or ten minutes, or any other interval for which the device may be designed.

By my invention it is optional with the user of the clock to cut off the main alarm so after the sounding of the one-stroke incipient alarm, or to let the alarm take its full course, according to circumstances and requirements.

What I claim as my invention and desire to secure by Letters Patent is:

In alarm clock mechanism of the character designated, the combination with the alarm escapement wheel of a spring pawl formed with a detent shoulder for engagement with the teeth of said alarm escapement wheel and also with a detent tooth of greater projection than said detent shoulder, an alarm setting spindle having a feeler finger rigidly attached thereto, a cam wheel slidably and rotatably mounted on said alarm setting spindle and formed with a hub contacting with said spring pawl, and an annular cam on said wheel contacting with said feeler finger on the alarm setting spindle and formed with minor and a major cam depressions, for the purpose, and substantially in the manner set forth.

ROBERT S. WATT.
